CLAIM

The ornamental design for a precleaner adapter kit, as shown and described.

DESCRIPTION

FIG. 1 is a front perspective view of an adapter kit showing my design;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines shown in the drawings are included for purpose of illustrating environmental structure and form no part of the claimed design.
